UNITED STATES PATENT OFFICE.

GABRIEL GUTLOHN, OF PHILADELPHIA, PENNSYLVANIA.

DESIGN FOR A HAT-TRIMMING.

SPECIFICATION forming part of Design No. 22,645, dated July 25, 1893.

Application filed June 26, 1893. Serial No. 478,895. Term of patent 3½ years.

To all whom it may concern:

Be it known that I, GABRIEL GUTLOHN, a citizen of the United States, residing at Philadelphia, in the county of Philadelphia and State of Pennsylvania, have invented a certain new and useful Design for a Hat-Trimming, of which the following is a specification.

My invention has relation to millinery and has for its object the provision of a novelty,—
as illustrated in the accompanying drawing, which is a plan view thereof,—designed and adapted for use in trimming hats, &c., the same presenting a new and original design, for the purpose mentioned, comprising a laterally extending head and a portion of the body or the neck of an animal, and a number of spirals or helices of varying lengths pro-

jecting radially from a common center, at the side or end of the body or neck portion of the aforesaid animal, and terminating each in a fuzzy ball or sphere, the whole emanating from or surmounting a stock or stem common to all.

What I claim as my invention, and desire to secure by Letters Patent, is—

The design for a trimming for hats, &c., substantially as herein shown and described.

In testimony whereof I have hereunto set my hand this 21st day of June, A.D. 1893.

GABRIEL GUTLOHN.
